UNITED STATES PATENT OFFICE

2,382,146

PROJECTILE GAME

Frank C. Hamilton, Newark, N. J.

Application September 29, 1943, Serial No. 504,237

2 Claims. (Cl. 273—101)

This invention relates to amusement devices of the type which include a projectile, one object of the invention being to provide a novel and improved device of this character which shall simulate the circus performance of shooting a man from a cannon, the operation of which shall provide amusement and involve both skill and chance.

Another object is to provide an amusement device or game apparatus which shall comprise a novel and improved construction and combination of target or scoring elements, for example in simulation of trapezes, a projectile to be suspended therefrom, for example a representation of a man, and means for propelling or shooting said projectile to said target or scoring elements.

A further object is to provide such amusement apparatus wherein the construction of said target or scoring elements shall be such that the force of impact of said projectile with a target or scoring element shall be compensated or partially absorbed to obviate such rebounding of the projectile as would prevent suspension of the projectile on the target or scoring element.

Other objects are to provide a novel and improved projectile for amusement apparatus of the character described; to provide amusement apparatus which shall be simple and inexpensive in construction and which shall require a minimum of materials use of which is now restricted due to the current world war; and to obtain other advantages and results that will be brought out by the following description in conjunction with the accompanying drawing in which

Figure 1 is a perspective view of an amusement apparatus embodying my invention.

Figure 2 is an enlarged longitudinal vertical sectional view through the projector.

Figure 3 is a fragmentary transverse vertical sectional view on the line 3—3 of Figure 1.

Figure 4 is a front elevational view of the projectile and

Figure 5 is a side elevational view thereof.

Specifically describing the illustrated embodiment of the invention the apparatus includes a base A on one end portion of which is a plurality of vertical supports or standards 1 upon which are mounted a plurality of target or scoring elements 2. At the other end portion of the base A is a projector B for propelling against the target or scoring elements 2 a projectile C having means to engage said elements.

Each scoring element is shown as comprising a strand of suitable material which is mounted on the corresponding support standards 1 to yield

under the impact of an object, such as the projectile C, therewith. Preferably the strands are formed of flexible material and means is provided normally to hold each strand taut between the points of connection thereof with the standards 1 and to allow the strand to flex when it is struck by the projectile.

As shown, each of the standards comprises a strip of suitable material such as wood that has one end secured at 3 to the base A and at its other end has a transverse horizontal opening 4. Each standard is arranged at one side of the base in opposed relation to a standard at the other side of the base and the opening 4 of each standard is in horizontal alignment with the corresponding opening of the opposite standard. Suitable braces 5 may be provided for holding the standards in vertical position.

Each strand 2 has one end slidably threaded through the opening 4 of one of each of two opposed standards 1, and each end of each strand has a weight 6 attached thereto and suspended therefrom so that the two weights maintain the portion of the strand between the standards normally taut but will permit said portion of the strand to flex under impact of the projectile. Of course, one weight would be sufficient and if desired springs or other suitable means might be utilized for the same purpose.

As shown, the strands 2 are approximately parallel to each other and in horizontally spaced relation so as to simulate trapezes, although the strands may be otherwise arranged if desired. The projectile C represents a clown and the projector B represents a cannon so that the apparatus is in simulation of the circus stunt comprising the shooting of a man from a cannon. The projectile comprises a body 7 having a plurality of hooks 8 pivotally connected thereto, said hooks in the present instance representing the feet and hands of a human being. As shown, the hooks at each side of the body swing in a common plane from front to rear of the body, although the hooks may be constructed and connected to the body in any suitable manner.

The projector B comprises a barrel 10 having an interior diameter of sufficient size to receive the projectile C and within the barrel is reciprocable a spring actuated plunger or piston 11 which normally is influenced outwardly of the barrel by a compression spring 12. The plunger is connected to a trigger block 13 that is also slidably in the barrel and has a notch 14 which cooperates with the trigger 15. The trigger is pivotally mounted intermediate its ends, as at 16, on the

barrel and has a head 17 at one end to engage the notch 14 and a finger piece 18 at the other end for oscillation of the trigger. A finger-piece 19 for manually actuating the plunger against the influence of the spring 12 to set or cock the projector is attached to the trigger block 13.

In operation of the projector, the trigger block and plunger are pushed by the finger piece 13 to energize the spring 12 and to bring the notch 14 into engagement with the trigger 15, as shown by dot and dash lines in Figure 2. The projectile C is then inserted into the barrel and in contact with the plunger 11. Then the trigger is operated to release the plunger, whereupon the spring and plunger will project or shoot the projectile out of the barrel.

It is desirable that the projector be capable of tilting so that the operator may cause the projectile to engage one or more selected strands 2 and for this purpose the barrel 10 is pivotally mounted on a horizontal axis as by pins or trunnions 20 projecting diametrically from the barrel and journaled in bearing standards 21 on the base A. A handle or crank 22 may be connected to one of the pivot pins 20 for oscillating the barrel in the bearings 21. With this construction it will be seen that the barrel can be swung in vertical planes to vary the trajectory of the projectile.

In use of the apparatus, the operator will cock the projector and insert the projectile in the barrel. He then will aim the barrel with the idea of causing the projectile to engage one or more of the targets or scoring strands 2, probably selecting the strands which have the greatest scoring value. He will then operate the trigger 18 to release the plunger 11 and the projectile will be shot upwardly. If the projector is properly aimed, one or more of the hooks 8 of the projectile will engage and hook over one or more of the strands 2 as shown by dot and dash lines in Figure 1. As the hooks engage the strands, the weight of the projectile and the force of its impact will cause the strands to flex between the strands 1 as shown by dot and dash lines, whereby the force of the impact of the projectile against the strands will be compensated or absorbed in such a manner that rebound of the projectile will be prevented.

For convenience, the scoring indicia may be placed on the weights 6 as indicated at 23.

To enhance the simulation of the circus stunt as well as to in some degree restrain the projec-

tile, a net 24 may be arranged beneath the scoring strands. As shown, one end of the net is connected to a rod 25 which is mounted between two opposed standards 1, while the other end of the net is mounted on a rod 26 which is secured in bracket arms 27 disposed at opposite sides of the base and held in upright position by braces 28. If desired, the braces 28 may be detachable at 29 from the bracket arms so that the latter can be swung inwardly over the base into an out-of-the-way position.

Also, for convenience the base may be formed in two sections 30 and 31 which may be arranged in end to end alinement with each other as by pins 32 on the end of one section to fit corresponding sockets 33 in the juxtaposed end of the other section.

Various modifications and changes in the details of construction of the apparatus will occur to those skilled in the art as within the spirit and scope of the invention.

What I claim is:

1. An amusement apparatus including a flexible strand, means mounting said strand at two spaced points at one of which said strand is longitudinally movable, an aerial projectile having at least one hook to hook over said strand, and means to normally hold said strand taut between said points and to allow the strand to move longitudinally and flex upon impact of said projectile therewith, whereby when said projectile is projected it may become suspended upon said strand.

2. Amusement apparatus including a base having spaced and opposed vertical support elements thereon, a plurality of horizontal flexible strands on said support elements, each mounted at two spaced points at one of which said strand is longitudinally movable, an aerial projectile including a body and at least one hooked arm pivotally connected to each end thereof, said strands being in horizontally spaced relation and said hooked arms being in spaced relation on said body, so that said hooked arms may simultaneously engage different strands, and means to normally hold each strand taut between said two points and to allow the strand to move longitudinally and flex upon impact of said projectile therewith, whereby when said projectile is projected it may become suspended on one or more of said strands.

FRANK C. HAMILTON.
